US00D851066S

(12) **United States Design Patent** (10) **Patent No.:** **US D851,066 S**
(45) **Date of Patent:** **** Jun. 11, 2019**

(54) **ACOUSTIC DEVICE**

(71) Applicant: **Dong Guan Jia Sheng Lighting Technology Co., Ltd. China**,
Dong-Guna, Guang-Dong (CN)

(72) Inventor: **Kevin Hsu**, Taichung (TW)

(73) Assignee: **Dong Guan Jia Sheng Lighting Tehcnology Co., Ltd. China**,
Guang-Dong (CN)

(**) Term: **15 Years**

(21) Appl. No.: **29/616,556**

(22) Filed: **Sep. 7, 2017**

(51) LOC (11) Cl. **14-01**

(52) U.S. Cl.

USPC **D14/209.1**

(58) **Field of Classification Search**

(57) **CLAIM**

The ornamental design for an acoustic device, as shown and described.

DESCRIPTION

FIG. 1 is a perspective view of an acoustic device showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 6 Drawing Sheets
